Carpets

No. 5,647

Mar. 12, 1872

5,647

UNITED STATES PATENT OFFICE.

ARCHIBALD McCALLUM, OF HALIFAX, ENGLAND, ASSIGNOR TO JOSEPH WILD & CO., OF NEW YORK CITY.

DESIGN FOR A CARPET-PATTERN.

Specification forming part of Design No. 5,647, dated March 12, 1872.

Specification describing a new and original Design for Carpets, invented by ARCHIBALD McCALLUM, of Halifax, in the county of York, England.

The accompanying photograph represents my new design.

This invention relates to a new design for a carpet, which contains three different styles of figures, A, B, and C.

A is a square, containing an ornamental cross and surrounded by an ellipse, D, with pointed ends. B is a square figure, containing a quatrefoil, a, and embraced within a mixt-linear octagon, E. C is a square figure, containing interior squares and ornamented, as shown.

I claim as my invention—

1. The design of the figure A, as shown.
2. The design of the figure B, as shown.
3. The design of the figure C, as shown.
4. The design for the carpet, containing the figures A, B, and C, as shown.

ARCHIBALD McCALLUM.
